(57) **CLAIM**

The ornamental design for a multiple implement outdoor tool, as shown and described herein.

DESCRIPTION

FIG. 1 is a perspective view of the multiple implement outdoor tool, with the handle end of the tool oriented toward the bottom of the page, showing our new design;

FIG. 2 is top plan view of the multiple implement outdoor tool;

FIG. 3 is bottom plan view of the multiple implement outdoor tool;

FIG. 4 is a side elevation view of the multiple implement outdoor tool, with the handle end oriented to the left;

FIG. 5 is a side elevation view of the opposing side of the multiple implement outdoor tool as shown in FIG. 4;

FIG. 6 is an end elevation view of the multiple implement outdoor tool, depicting the handle end of the tool; and,

FIG. 7 is an end elevation view of the multiple implement outdoor tool, depicting the shovel head end of the tool.

1 Claim, 4 Drawing Sheets
